UNITED STATES PATENT OFFICE.

MICHAEL E. SULLIVAN, OF NEW BEDFORD, MASSACHUSETTS, ASSIGNOR TO
SAWYER SPINDLE COMPANY, OF MAINE.

SPINNING-SPINDLE.

SPECIFICATION forming part of Letters Patent No. 728,042, dated May 12, 1903.

Application filed January 10, 1903. Serial No. 138,477. (No model.)

To all whom it may concern:

Be it known that I, MICHAEL E. SULLIVAN, a citizen of the United States, and a resident of New Bedford, county of Bristol, State of Massachusetts, have invented an Improvement in Spinning-Spindles, of which the following description, in connection with the accompanying drawings, is a specification, like letters on the drawings representing like parts.

This invention relates to spinning-spindles; and it has for its object the production of novel, simple, and effective means for preventing slipping of the yarn-carrier or bobbin or upward displacement thereof due to centrifugal action.

In accordance with my invention the spindle is provided above the whirl with a flexible and preferably elastic disk-like downhold, the periphery thereof frictionally engaging the interior of the bobbin when pushed down into operative position. The application of the bobbin acts to slightly depress the peripheral portion of the downhold, and any slipping or lifting movement of the bobbin relative to the spindle is prevented by the inherent resistance of the downhold.

The various novel features of my invention will be described in the subjoined specification and particularly pointed out in the following claims.

Figure 1 is a side elevation and partial vertical section of a spinning-spindle with one embodiment of my invention applied thereto, the yarn-carrier or bobbin being shown in section in operative position. Fig. 2 is a side elevation of the whirl-supporting sleeve, broken out at its upper end, with the downhold thereon with the bobbin omitted; and Fig. 3 is a transverse sectional view on the line 3 3, Fig. 1, looking down.

The rotatable spindle A, its supporting-case A^X, adapted to be attached to the spindle-rail in usual manner, and the whirl W, connected with the spindle by a downturned sleeve w, are all of well-known construction to those skilled in the art.

As shown in Fig. 1, the yarn-carrier or bobbin B is hollowed out internally at its lower end at b to receive the upper end of the sleeve w when the bobbin is pushed down thereupon,

the sleeve being slightly tapered externally in usual manner.

In the present embodiment of my invention I make a rather deep annular external groove 55 w^X in the sleeve near its upper end, and the downhold d is seated therein and held in place. The downhold is a disk-like piece of flexible and preferably elastic material—such as rubber, leather, &c.—having a central hole 60 to enable it to be slipped over the upper end of the sleeve and into the groove w^X. The external diameter of the downhold is slightly greater than the inside diameter of the hollowed portion b of the bobbin, and preferably 65 the periphery is notched or non-continuous, as at d^X, Fig. 3, to increase the flexibility of the downhold at its periphery and also to provide a plurality of engaging portions. When the bobbin is pushed down into place, 70 the periphery of the downhold engages the interior of the bobbin and is bent downward somewhat, as shown in Fig. 1, so that there is a firm frictional engagement between the downhold and bobbin. The inherent resist- 75 ance of the downhold prevents any slipping of the bobbin on the sleeve and also prevents the latter from being thrown upward by centrifugal action. A positive upward pull on the bobbin readily disengages it when it is 80 necessary to doff.

The downhold obviates forcing the bobbin down hard upon the sleeve and prevents splitting of the hollow end of the bobbin.

Having fully described my invention, what 85 I claim as new, and desire to secure by Letters Patent, is—

1. A spinning-spindle having an attached whirl, and a flexible and elastic disk-like downhold rotatable with and extended laterally 90 from the spindle above the whirl, to frictionally engage the interior of a bobbin and prevent slipping and upward movement thereof when the spindle is running.

2. A spinning-spindle having a downturned 95 whirl-supporting sleeve secured thereto and provided with an annular groove near its upper end, and an annular, flexible, elastic downhold held in the groove and having a non-continuous periphery to engage the interior 100 of a bobbin and retain it in position on the sleeve.

3. A spinning-spindle having a whirl-supporting sleeve provided with an annular groove above the whirl, and an annular, laterally - extended downhold seated in the 5 groove, and having a flexible and elastic notched periphery, to engage the interior of and retain a bobbin in position on the sleeve.

In testimony whereof I have signed my name to this specification in the presence of two subscribing witnesses.

MICHAEL E. SULLIVAN.
